CONTINUOUS MANUFACTURE OF FIBROUS MATERIAL

John Page, Evanston, Ill., assignor to United States Gypsum Company, Chicago, Ill., a corporation of Illinois

Application January 10, 1939, Serial No. 250,156

7 Claims. (CL 83—94)

The present invention relates to a continuous process of producing finely divided fibrous material in definitely controllable quantities so that it may be continuously fed into cementitious materials as a filler without becoming clumped or aggregated.

The invention is particularly important in connection with the production of a fibrous filler to be used in the continuous production of a gypsum-core wallboard.

The uniform continuous addition of small but definite amounts of fibrous material, for example a cementitious mixture such as is used for the core of a plaster board, is very difficult to accomplish, no matter how many precautions are taken to insure uniform feed of fibrous material. For example, in a plaster board core mixture sufficient to produce 1000 square feet of $\frac{3}{8}$ -inch board, it is desirable to add from 8 to 20 pounds of finely ground waste newspaper fibers to as much as 1200 pounds of calcined gypsum, together with other materials employed to modify the latter. It will be self-evident that the uniform intermingling of these proportions of newspaper fibers and calcined gypsum presents unusual difficulties. Inasmuch as such wallboard is produced in a continuous manner in a continuously operating machine, it becomes necessary to effect the mixture of the fibers with the gypsum and the gauging water in a continuous manner, mixing only small amounts at a time. Therefore the problem becomes even more difficult than would be the case if a large quantity of fibers could be mixed with a large quantity of gypsum. Many attempts have been made to provide for uniform flow of fibrous substance to such a gypsum mixture, but until the advent of the present invention such uniform feed has not been successfully accomplished. For example, the addition of the fibers from a bin or hopper containing the fibrous aggregate or agglomerate described in the copending application of George D. King, Serial No. 250,165, filed January 10, 1939, may present certain difficulties. The material may pack down in a storage bin due to the weight of the superimposed material, so that the density of the substance at the bottom of the hopper will be greater than at the top and, if screw feed be employed, different weights of material will be fed, depending upon the amount of material in the bin. Inasmuch as the screw feeders are usually geared to the rate of operation of the machine, it will be self-evident that uniform feed of the fibrous material may become diffi-

cult; and only if the apparent density of the material being fed is kept uniform can uniform addition in a continuous operation be accomplished. For example, the fibers described in the said King application are of a very fluffy nature, weighing approximately 2 pounds per cubic foot, but they are easily compressed; and in a hopper 4 feet high the density varies so greatly from the bottom to the top that the conventional feeding means hitherto employed become quite unreliable. If on the other hand a weight proportioning device is employed, careful control of the weight of the fibers also may present difficulties. Thus, variations in temperature, humidity, and the like will materially affect the amount of fibers effectively fed. Although in the copending King application already referred to the method of making the fibrous product of the present invention and the product itself are broadly disclosed and claimed, by the present invention it becomes possible to produce the King product in a continuous manner under such conditions that its uniform feed into a cementitious slurry becomes feasible and controllable. It will of course be apparent, in view of the details hereinafter given, that the objectives aimed at may be accomplished in a number of ways, all of them, however, being within the spirit and scope of the present invention.

Therefore, the primary purpose of the present invention is to provide a means and method for continuous production of a fibrous aggregate, of the type described in the said King application, in a continuous stream, which can be controlled as to its weight and characteristic properties so that, by proper co-ordination of the speed of operation of the instrumentalities described herein with the speed of production of the wallboard machine for example, uniform incorporation of the fibrous aggregate with the plaster slurry can be effectively accomplished. One way of obtaining uniform and continuous addition of fiber is described in the copending application of Welty, Page & Bygden, Serial No. 250,152, filed January 10, 1939. In the said Welty, Page & Bygden process a continuous sheet of waste trimmed from a paper-making machine is continuously disintegrated and added in a fibrous condition to a cementitious mixture. In the present invention, however, continuous as well as discontinuous sheets may be employed because of the apparatus set-up and the interconnection of the various instrumentalities about to be described.

In the one-sheet drawing filed concurrently herewith and forming a part of the present specification there is illustrated in diagrammatic form one of the preferred embodiments of this invention. Referring to the said drawing, it will be seen that the invention may consist of a chip-forming mill A, a chip separator B, a chip hopper C, a spiked drum and co-operating brush D, a fiberizing mill E, a pneumatic duct F, a fiber separator G, and a screw conveyor H. In operating this combined apparatus, waste paper is fed into the chip-forming mill A through a chute 1. This mill A is of the swing-hammer type, being actuated by a suitable electric motor 2 through a coupling 3 on a shaft 4. This chip-forming mill reduces the large sheets of newspaper to flake-like particles which are educed from the mill A through conduit 5 and thereby transported to chip-separator portion 6 of the separator B. A blast of air, created by a fan 7 which is actuated by a pulley 8 mounted upon the aforementioned shaft 4 and a belt 9, conveys the flake-like particles through the conduit 5. In the chip separator 6, which is built in the form of a cyclone separator, the air is separated from the small paper chips and passes out through an air vent 10, the chips falling downwardly through a chip hopper 11. At this stage of the operations the flake-like material possesses sufficient resiliency to withstand packing; and the chip hopper is so constructed as to prevent any arching or bridging therein as it becomes filled. It should be noticed that the upper portion of the chip hopper is constricted while the lower part 12 is expanded and leads to a rotatable spiked drum 13. The enlargement 12 prevents the arching or bridging of the chips or flakes and also aids in preventing the packing thereof as a result of the weight of the fibrous material. The paper chips are drawn from the chip hopper 11 by means of the spiked drum 13 which forms the lower obturating portion of the enlarged section 12. The spiked drum 13 may revolve in a counterclockwise direction as seen on the drawing and is indicated by the arrow thereon, thus carrying the flakes out of the chamber 12 and discharging them in the form of individual flakes into a hopper 14. The spikes are relieved of any flakes by means of a rotating brush 15 which intermeshes with the spikes on the spiked drum 13. A retaining wall 16 at the lower part of the chip separator portion D prevents any of the particles from falling in the other direction, the result being that there will be a continuous feed of paper flakes down through the hopper 14, so that there will be a veritable snowstorm of flakes being continually fed into a disintegrating or hammer mill 17. The feeding of the paper flakes from the chip hopper 12 to the hopper 14 may be further controlled by a small plate 11a extending from the side walls of the chip hopper 12 toward the spikes on the drum 13. The plate 11a serves to prevent extrusion of the flakes between the drum 13 and brush 15 in excessive quantities.

By reason of the continuously and freely falling feed of paper, the output of this mill may be accurately controlled by regulating the speed of rotation of the spiked drum 13. The mill is of standard construction and contains at the bottom thereof a screen 18 which will retain the small unfiberized flakes or confetti in the mill and prevent them from passing through the screen. The sloping side wall 18a may be broken as shown to provide a vent 18b. The sufficiently

ground fibers pass through the screen 18 and fall into a duct 19 from which, by means of a fan 20 (actuated by an electric motor 21) they are caused to pass into the duct F which conducts them into the fiber separator G, in which the cyclonic effect whirls them into little aggregates which are continuously discharged through a conduit 23. The air is drawn into the fiberizing mill 17 through the vent 18b. The air passes along the side walls of the hopper and prevents the paper flakes from collecting thereon, so that they are continuously drawn into the fiberizing mill 17.

The major portion of the air is separated from the ground fiber aggregate in the separator G through a vent 24. Within the fiber separator there is a deflecting plate or baffle 25 to give the fibers a suitable downward impetus. This baffle 25 not only slows down the centrifugal force and thus releases the major part of the moving influence but also diverts a small portion of the stream and directs it along the walls of the separator. The fibers, being of a very fine fluffy nature, have a marked tendency to adhere to the walls of the separator and to accumulate thereon. This film increases in thickness until the weight thereof breaks at the point between it and the walls and the entire mass slides down the chute or conduit 23. This of course is highly undesirable because it will produce surges in the otherwise uniform distribution of the fibers which enter the screw conveyor H through the conduit 23. This screw conveyor H feeds the comminuted fiber to the plaster-board forming machine. In order to overcome this possible surging of the fibrous material, the aforesaid baffle means 25 is wound spirally around the inside of the air separator G, thus deflecting a portion of the air stream, which thus scouring the walls of the chamber and keeps it free from the particles which would otherwise cling thereto. Only a very small portion of the air stream needs to be thus deflected, but it will serve to keep the walls of the air separator clean; and this feature causes the continuous discharge from the separator of a constant uniformly dense stream of comminuted fiber which is collected by the screw conveyor 26 and continuously conveyed to the plaster-board machine. The excess air from the material is vented through an air vent 27.

In accordance with the above described apparatus, the steps for carrying out the process of uniformly feeding paper fibers to the cementitious material may comprise:

- 55 (1) The formation of a flake-like material from a sheet or scrap of cellulosic material such as waste newspaper;
- 60 (2) The feeding of this flake-like material by means of a spiked drum in a uniform manner and in uniform quantities to a second fiberizing mill;
- 65 (3) The comminution of these particles in the said fiberizing mill at a uniform rate and to a uniform degree of comminution;
- 70 (4) The collection of the fibers from the fiberizing mill in a continuous and uniform manner; and
- 75 (5) The uniform feeding of fiberized material of substantially constant apparent density to the point of discharge or point of admixture with the cementitious material into which it is introduced as a filler.

It will be apparent that the speed of the two mills can be so co-ordinated with the speed of

the production of the wallboard or other plastic-material machine that a constant supply of comminuted fiber can be obtained, so that accurate control of the amount of fibers introduced into the plastic mass can be assured. So far as the applicant is aware, no one has hitherto attempted to produce simultaneously with the production of a plastic slurry a constant supply of uniformly comminuted fibrous filling material; and this feature of the present invention is believed to be broadly new.

Inasmuch as the chip-forming mill and the fiberizing mill are standard equipment, it is unnecessary for the purpose of the present invention to describe them in any mechanical detail; and the detailed construction of the spiked drum and brush is so obviously indicated on the drawing that detailed sectional drawings thereof are unnecessary, as any well trained mechanic will be able to construct a device like that shown in the drawing by merely following it and employing his mechanical knowledge. Suitable trunnions, shafting and means for applying motive power to the spiked drum 13 and the brush 15 are of course provided, although they are not shown in the drawing, as they are not new in themselves and are not new in the industry.

While the spiked drum and the brush are shown as particularly efficacious means for feeding chips or flakes to the disintegrating or fiberizing mill, equivalent constant-feed devices may be substituted therefor without departing from the fundamental principles of the present invention, and such substitution is to be construed as strictly within contemplation of the inventor and to be encompassed within the scope of his claims.

Saving for himself such equivalents as will readily occur to those skilled in the art to which this application pertains, the inventor claims:

1. The process of continuously and uniformly producing a stream of loosely interlaced bulky fibrous material which comprises the steps of feeding fibrous sheets to a comminuting means of the hammer-mill type in which said sheets are initially reduced to flaked form, pneumatically moving the thus produced flakes to a cyclone air separator and from the latter discharging the flakes to a hopper adapted to prevent the packing of the flakes therein, uniformly and continuously removing a predetermined bulk of said flakes from said hopper and feeding it continuously and uniformly into a second comminuting means of the hammer-mill type in which said flakes are comminuted essentially to their initially fibrous condition, pneumatically transferring the thus formed fibers to a second cyclone separator and swirling them therein to cause them to form loosely interlaced small fibrous aggregates, and removing said aggregates by means of a blast-deflecting device from said swirling zone at a continuous and uniform rate.

2. Apparatus for the continuous production of a uniform supply of comminuted fibrous material which comprises the combination of a chip-forming mill having swing-hammer comminuting means therein, a pneumatic chip separator therewith connected, said chip separator being characterized by having a narrowed portion therein to prevent bridging of the therein collected chips; means at the bottom of said chip separator for uniformly removing therefrom predetermined quantities of the therein accumulating chips; means for feeding said chip stream to a fiberizing mill; a fiberizing mill provided with comminuting means of the swing-hammer type, 75

said fiberizing mill being provided with sifting means for retaining insufficiently comminuted chips and for passing sufficiently comminuted fibers; pneumatic conveying means leading from 5 said fiberizing mill; a separator into which said pneumatic conveying means feeds, said separator being provided with an internal baffle to obtain deflection of the air currents entering the same, so as to produce swirling movement of the fibrous particles therein, whereby they become aggregated to form loosely intertwined aggregates of fibers; discharge means on said separator comprising a downwardly directed chute, and a screw conveyor into which said chute leads for conveying to any determined point the product issuing from said chute.

3. Apparatus for the continuous production of a uniform supply of comminuted fibrous material which comprises a chip-forming mill of the swing-hammer type, a pneumatic conveyor therewith connected leading to a chip separator, a chip separator of the cyclone type and provided with a narrowed portion leading to a chip hopper; a chip hopper the bottom of which is closed by means of a chip-feeding mechanism which itself comprises the combination of a rotatable cylindrical drum provided with peripheral spikes extending therefrom and a therewith co-operating rotary brush and means for rotating said spiked drum and brush; a fiberizing mill and means for feeding the chips delivered by said spiked drum to said fiberizing mill, the latter being of the swing-hammer type and provided with sifting means to separate insufficiently ground from sufficiently ground material; pneumatic means connected with said fiberizing mill for conveying the therein produced fibers to a fiber separator, a fiber separator having a conical bottom and provided at a point near the intake thereof with a spiral baffle to cause the incoming fiber-laden air stream to assume a spiral course, whereby the fibers are separated and caused to agglomerate into small fibrous aggregates; means on said separator, comprising a chute, for continuously discharging the fibrous aggregates produced in the separator; and a conveying means connected with said chute for transporting the aggregates to their point of use.

4. An apparatus for continuously mixing a stream of disintegrated paper fibers with a stream of cementitious material which comprises a conveyor means for providing a uniform and continuous flow of cementitious material, a mill of the swing hammer type for comminuting a paper web into flake form, a comminuting means for fiberizing the flakes thus produced, a temporary flake storage chamber positioned between said mill and said comminuting means, a pneumatic conveyor means including an air separator for conveying said flakes from said mill to said temporary storage chamber, a positive feeding mechanism associated with the discharge end of said chamber for introducing said flakes into said comminuting means at a substantially uniform, constant, predetermined rate, means for introducing said paper web into said mill, and pneumatic means including a second air separator for discharging the resulting stream of disintegrated paper fibers from the comminuting means at said predetermined rate into said conveyor means whereby a continuously advancing mixture containing constant proportions of fibers and cementitious material is produced.

5. An apparatus for continuing mixing a

stream of disintegrated paper fibers with an advancing stream of cementitious material which comprises a screw conveyor means for providing a uniform and continuous flow of cementitious material, a swing hammer mill for comminuting an advancing paper web into flake form, a comminuting means for fiberizing the flakes thus produced, a temporary flake storage hopper positioned between said mill and said comminuting means, a pneumatic conveyor means including a cyclone separator for conveying said flakes from said mill to said temporary storage chamber, a positive feeding mechanism including a rotatable spiked drum and cleaning brush associated with the discharge end of said chamber for introducing said flakes into said comminuting means at a substantially uniform, constant, predetermined rate, means for introducing said paper web into said mill in a continuous sheet, and pneumatic means including a second cyclone separator for discharging the resulting stream of disintegrated paper fibers from the comminuting means at said predetermined rate into said screw conveyor means, whereby a continuously advancing mixture containing constant proportions of fibers and cementitious material is produced.

6. An apparatus for the continuous production of a uniform supply of comminuted fibrous material which comprises a chip forming mill of the swing hammer type, a conveyor including a pneumatic chip separator connected therewith leading to a chip hopper, a chip hopper, a chip fiberizing mill, a separately operated rotat-

able spiked drum mechanism adapted to remove chips from said hopper to said fiberizing mill at a substantially uniform rate, and pneumatic means for discharging comminuted fibrous materials from said fiberizing mill at said uniform rate, also said pneumatic means including a separator of the cyclone type.

7. The continuous process of uniformly incorporating a loose fibrous material with a cementitious material which comprises partially disintegrating by impact a web of paper to a confetti-like mass, passing said mass through an air separating zone, collecting said mass in a temporary storage zone, separately and continuously removing said mass from said storage zone and causing it to flow at a substantially constant rate, further disintegrating said mass to the fibrous state at the rate at which it is removed from said storage zone, discharging the resulting fibrous mass into a second air separating zone, separately providing a continuously moving stream of said cementitious material, continuously discharging a constant stream of the fibrous mass from said second air separating zone into said stream of cementitious material, and controlling the rate at which the confetti-like mass passes from said temporary storage zone to the zone of final disintegration in accordance with the rate of movement of said stream of cementitious material whereby the proportion of fibrous material to the cementitious material in the final mix is maintained substantially constant.

JOHN PAGE.
